(57) **CLAIM**

The ornamental design for a skate, as shown and described.

DESCRIPTION

FIG. 1 is a perspective view of a skate in accordance with our new design.

FIG. 2 is a first side elevational view of the design of FIG. 1.

FIG. 3 is a front elevational view of the design of FIG. 1.

FIG. 4 is a rear elevational view of the design of FIG. 1.

FIG. 5 is a second side elevational view of the design of FIG. 1, opposite the first side.

FIG. 6 is a bottom plan view of the design of FIG. 1; and, FIG. 7 is a top plan view of the design of FIG. 1.

Any parts shown in broken lines form no part of the claimed design.
